DESIGN FOR A COMBINED COIN AND KEY PURSE OR SIMILAR ARTICLE

Daniel J. Nash, New York, N. Y.

Application October 3, 1944, Serial No. 115,563

Term of patent 14 years

(Cl. D87—3)

To all whom it may concern:

Be it known that I, Daniel J. Nash, a citizen of the United States and a resident of the Borough of Manhattan, in the city, county, and State of New York, have invented a new, original, and ornamental Design for a Combined Coin and Key Purse or Similar Article, of which the following is a specification, reference being had to the accompanying drawing, forming a part thereof, in which

Figure 1 is a front elevational view in closed

position of a combined coin and key purse, or similar article, showing my new design;

Fig. 2 is a side elevational view thereof with the cover open;

Fig. 3 is a top view thereof with the cover open; and

Fig. 4 is a section on the line 4—4 of Fig. 3.

I claim:

The ornamental design for a combined coin and key purse or similar article, as shown.

DANIEL J. NASH.
